US0D1036007S

(12) **United States Design Patent** (10) **Patent No.:** **US D1,036,007 S**
(45) **Date of Patent:** **** Jul. 16, 2024**

(54) **TWEEZER**

(71) Applicant: **Jianrong Zeng**, Guangzhou (CN)

(72) Inventor: **Jianrong Zeng**, Guangzhou (CN)

(73) Assignee: **Jianrong Zeng**, Guangzhou (CN)

(**) Term: **15 Years**

(21) Appl. No.: **29/926,263**

(22) Filed: **Jan. 30, 2024**

(51) **LOC (14) Cl.** **28-03**

(52) **U.S. Cl.**

USPC **D28/55**

(58) **Field of Classification Search**

USPC D28/4, 7, 9, 25, 55, 99; D24/133, 143

CPC B25B 9/02; A45D 26/00; A45D 26/0066;

G04D 1/021; A61B 2017/305
